US0D1019617S

(12) **United States Design Patent** (10) **Patent No.:** **US D1,019,617 S**
(45) **Date of Patent:** **** Mar. 26, 2024**

(54) **ANTENNA**

(71) Applicant: **TALLYSMAN WIRELESS INC.**, Kanata (CA)

(72) Inventors: **Gyles Panther**, Ottawa (CA); **Julien Hautcoeur**, Gatineau (CA); **Ken MacLeod**, Kanata (CA)

(73) Assignee: **Tallysman Wireless Inc.**, Kanata (CA)

(**) Term: **15 Years**

(21) Appl. No.: **29/811,684**

(22) Filed: **Oct. 15, 2021**

(30) **Foreign Application Priority Data**

Apr. 22, 2021 (CA) ..... CA 202981
(51) **LOC (14) Cl.** **14-03**
(52) **U.S. Cl.**
USPC **D14/230**

(58) **Field of Classification Search**

(57) **CLAIM**

The ornamental design for an antenna, as shown and described.

DESCRIPTION

FIG. 1 is a top perspective view of the antenna;
FIG. 2 is a bottom perspective view of the antenna depicted in FIG. 1;
FIG. 3 is a front elevation view of the antenna depicted in FIG. 1;
FIG. 4 is a rear elevation view of the antenna depicted in FIG. 1;
FIG. 5 is a left elevation view of the antenna depicted in FIG. 1;
FIG. 6 is a right elevation view of the antenna depicted in FIG. 1;
FIG. 7 is a top elevation view of the antenna depicted in FIG. 1; and,
FIG. 8 is a bottom elevation view of the antenna depicted in FIG. 1.

The antenna is shown with a symbolic break in its length. The appearance of the article between the break lines form no part of the claims design.

1 Claim, 6 Drawing Sheets
